UNITED STATES PATENT OFFICE.

STEPHEN W. BOURN, OF BRISTOL, RHODE ISLAND.

BRAIDER-CARRIER.

1,049,656.

Specification of Letters Patent.

Patented Jan. 7, 1913.

Application filed September 2, 1911. Serial No. 647,347.

To all whom it may concern:

Be it known that I, STEPHEN W. BOURN, a citizen of the United States, and resident of Bristol, in the county of Bristol and State of Rhode Island, have invented certain new and useful Improvements in Braider-Carriers, of which the following is a specification.

This invention relates to the spool-carriers of braiding machines and has particular reference to the means for releasing the thread so that it may be supplied as demanded.

Difficulty has heretofore been experienced in making a release mechanism which will operate accurately and satisfactorily at high speed and as a consequence the speed at which the machines may be run has been limited.

It has been my purpose to make a device which will permit an increase in speed and one which can be made at small cost and applied to the devices now in use.

The novel features of the invention will be apparent from the following description taken in connection with the drawings.

In the drawings: Figure 1 is a plan view of a device embodying my invention. Fig. 2 is a side view of the device. Fig. 3 is a plan view of one form of top plate and thread guide which I may use in carrying out the invention. Fig. 4 is a side view of the form shown in Fig. 3 placed in operative position. Fig. 5 is a front view of the bottom weight shown in Fig. 2.

In the drawings I have shown an ordinary form of standard or base 1 which is provided with the spindle 2 carrying the spool 3, which spool is ordinarily made of wood and has the ratchet teeth 4 at its top. The base or standard 1 has the shaft or bracket 5 preferably made integral therewith parallel to the spindle 2. On this bracket a bottom weight 6 and a top weight 7 are mounted in such way that they can slide vertically on the shaft with ease. The top weight 7 has an arm or pawl 8 which is adapted to engage the ratchet teeth 4 on the spool so as to limit the rotary motion of the spool. These features are common in devices of this class and the thread 9 from the spool ordinarily passes through the shaft 5 down beneath the lower weight 6 through a guide at the upper end of the shaft and to the place of use; and in operation it will be understood that the pull on the thread to supply the demand in use will elevate the weight 6, and when it is

carried high enough to strike the top weight 7 so as to elevate it above the ratchet teeth 4, the spool will turn and supply more thread. It has been found, however, in practical use that where the machines are run rapidly the lower weight will be thrown upward against the upper weight quickly and, owing to its momentum, it will carry the upper weight considerably above the ratchet teeth and the consequence is that the pull on the thread will turn the spool and unwind more thread than necessary. The result of this is that when the weight 6 descends it will go all the way to the bottom of the shaft 5 instead of being supported by the thread in the way shown in Fig. 2, and when this happens in the machines as ordinarily used the mechanism will be automatically tripped and stopped. Furthermore, the momentum of the lower weight is sometimes so great as to knock the upper weight entirely off the shaft or standard and consequently the machine is thrown out of operation. Efforts have heretofore been made to counteract this action of the lower weight, but the structures devised for that purpose have either been objectionable because of some feature of construction or operation. It has been my purpose to make an efficient device to overcome the objections with the least possible change in the old construction.

I have found that if a spring is placed above the upper weight 7 so arranged as to exert its downward pressure in line with the motion of the upper weight and so as not to tip the weight over and make it bind, decidedly better results will be secured in operation, and the device can be run at much greater speed without releasing any undue amount of thread at any one time. In the particular form shown in the drawings I make use of a bottom plate or ring 10 which rests on top of the ordinary upper weight and which has secured thereto a coiled spring 11 bearing down on the plate 10 directly in line with the motion of the weight 7. I preferably place a pin 12 in the arm 8 of the upper weight in such a position as to engage the ring 10 and hold it in proper position as shown. A top plate 13 of suitable construction is also secured to the upper end of the spring and this top plate engages the upper end of the shaft 5 so as to hold it in position and give the necessary pressure down upon the top weight 7. For convenience in fastening the spring in place I pref-

erably provide the top of the shaft 5 with a cross plate 14 having depending flanges 15 at its ends and the plate 13 is provided with an oblong slot 16 which will permit the passage of the plate 14 through it. On opposite sides of the slot 16 there are smaller openings 17, 18 adapted to receive the downwardly bent flanges 15 so that when the plate 13 is pushed down in position it is given a quarter turn and is then locked in place by the flanges 15 engaging the openings 17 and 18. The plate 13 is further provided with means for guiding the thread, and this means is made in such form as to offer as little resistance by friction as possible. In the form shown in Fig. 2 I make this guiding means of a bent wire 19, whereas in the modified form shown in Fig. 3 I make use of a flanged roller 20. In order to reduce the friction of the thread in passing beneath and supporting the lower weight 6 I also preferably make use of a roller 21 and where the thread passes through the shaft 5 I place means for reducing the friction, such as a porcelain collar 22.

I find that with a spring placed in line with the motion of the upper weight and with proper regulation of the tension of that spring I am enabled to increase very materially the speed at which the old type of device can be run. I find that the lower weight will be elevated by the pull on the thread and that by its momentum it will at the proper time raise the upper weight above the top of the teeth 4, permitting a limited rotation of the spool without imposing on the thread any undue strain in raising the upper weight, and I further find that the spring will at once push the upper weight down so as to prevent releasing too much thread. The anti-friction devices used by me furthermore assist greatly in securing greater speed.

Having thus described my invention what I claim as new and desire to secure by Letters Patent is:

1. In a device of the class described, the combination with an upright shaft, of top and bottom weights adapted to reciprocate thereon, the top weight being provided with means for engaging and limiting the turning motion of the bobbin, and yielding means exerting pressure directly in line with the force directed against the top weight tending to force said top weight down.

2. In a device of the class described, the combination with an upright shaft, of top and bottom weights adapted to reciprocate thereon, the top weight being provided with a pawl adapted to engage the bobbin head, and a spring exerting its pressure directly in line with the force directed against the top weight tending to force said top weight down.

3. In a device of the class described, the

combination with an upright shaft, of top and bottom weights adapted to reciprocate thereon, the top weight being provided with a pawl adapted to engage the bobbin head, and a coiled spring surrounding said shaft above said top weight tending to force said top weight down directly in the line of the movement of the bottom weight. 70

4. In a device of the class described, the combination with an upright shaft, of top and bottom weights adapted to reciprocate thereon, the top weight being provided with a pawl adapted to engage the bobbin head, a coiled spring surrounding said shaft above said top weight tending to force said top weight down directly in the line of the movement of the bottom weight, and anti-friction guides for the thread on said bottom weight and above said top weight. 75

5. In a device of the class described, the combination with an upright shaft, of top and bottom weights adapted to reciprocate thereon, the top weight being provided with a pawl adapted to engage the bobbin head, a coiled spring surrounding said shaft above said top weight tending to force said top weight down directly in the line of the movement of the bottom weight, an anti-friction guide for the thread in said shaft, and an anti-friction thread roller for said lower weight. 85

6. In a device of the class described, the combination with an upright shaft, of top and bottom weights adapted to reciprocate thereon, the top weight being provided with a pawl adapted to engage the bobbin head, a coiled spring surrounding said shaft above said top weight tending to force said top weight down directly in the line of the movement of the bottom weight, and means for detachably securing said spring in place on said shaft. 100

7. In a device of the class described, the combination with an upright shaft, of top and bottom weights adapted to reciprocate thereon, the top weight being provided with a pawl adapted to engage the bobbin head, a coiled spring surrounding said shaft above said top weight tending to force said weight down directly in the line of its motion, a plate against which the top of said spring bears, and quick detachable interlocking means between said plate and the top of said shaft. 110

8. In a device of the class described, the combination with a rotatable bobbin, of a shaft, top and bottom weights adapted to reciprocate on said shaft, the top weight being provided with means for limiting the turning motion of the bobbin and yielding means surrounding the shaft above the top weight tending to force said top weight down directly in the line of the movement of the bottom weight. 115

9. In a device of the class described, the

combination with a rotatable bobbin, of an upright shaft, top and bottom weights adapted to reciprocate on said shaft, the top weight being provided with means for engaging and limiting the motion of the bobbin, a coiled spring surrounding the shaft above the top weight tending to force said top weight down directly in the line of the movement of the bottom weight, and means 10 for detachably securing said spring in place

on the shaft comprising a plate against which the spring bears provided with slots and means engaging in said slots to prevent the outward movement of said plate.

In testimony whereof I affix my signature 15 in presence of two witnesses.
